UNITED STATES PATENT OFFICE.

JOHN THOMAS ELMORE, OF JACKSONVILLE, FLORIDA.

BURIAL VAULT.

1,411,331.

Specification of Letters Patent. Patented Apr. 4, 1922.

Application filed November 10, 1918. Serial No. 336,958.

To all whom it may concern:

Be it known that I, JOHN THOMAS ELMORE, a citizen of the United States, and a resident of Jacksonville, in the county of Duval and State of Florida, have invented certain new and useful Improvements in Burial Vaults, of which the following is a specification.

My invention relates to burial vaults and more particularly to burial vaults of the improved reinforced concrete type.

An important object of my invention is to provide an improved reinforced concrete burial vault in which the parts thereof are so constructed, arranged, and related as to be susceptible of easy and ready assembly to present a substantially unitary and hermetically sealed structure having inherent qualities of great strength and durability.

Another important object is to provide an improved reinforced concrete burial vault of this kind in which the hermetic seal may be easily broken from the outside of the structure to afford relief in the event of burial alive.

Other objects and advantages reside in certain novel features of construction, operation, and arrangement of parts as will be hereinafter pointed out in following description and appended claim, reference being had to the accompanying drawings, in which—

Figure 1 is a perspective view of my improved vault as it will appear assembled and in use;

Figure 2 is a view taken in vertical section on line 2—2 of Figure 1;

Figure 3 is a view taken in vertical section on line 3—3 of Figure 1;

Figure 4 is a perspective view of the cover showing the bottom side up;

Figure 5 is a detail view of the improved joint between the cover and the hollow receptacle.

Referring to the drawings, it will be seen that my invention includes in general a hollow receptacle indicated generally at A, preferably positioned in the ground, as shown in Figures 2 and 3; a cover indicated generally at B, adapted to be connected with the hollow receptacle in a manner to be hereinafter more fully described and to present the appearance shown in Figure 1; and a plastic bond indicated generally at C, adapted to cooperate with the physical features of construction and arrangement of the hollow receptacle and cover to unite said receptacle

and cover to form a substantially unitary structure, possessing, with respect to the exterior, all the qualities of strength and structural integrity with which a unitary, integral, and monolithic structure of this kind would be endowed; the material constituting the hollow receptacle and cover being preferably of concrete, although any substance of similar character may be employed, the concrete being water-proofed and finished to present the desired appearance.

The hollow receptacle comprises a bottom wall 10 and vertical side and end walls 11 and 12, respectively, which are preferably integral with the bottom wall and are disposed vertically or perpendicularly with respect to said bottom wall. The top edge or surface of the said side and end walls is provided with a groove 13 extending entirely around these top edges. The outer wall of this groove is inclined upwardly and outwardly, as shown at 14 in the drawings, and the inner wall 15 of this groove is vertical. An upstanding flange 16 is formed on the inner portion of the top edges of the side and end walls and extends entirely around said walls. The inner vertical wall of this flange is coincident with the inner wall of the hollow receptacle and the outer wall of this flange is coincident with the inner vertical wall of the groove 13.

The cover B has its marginal portion of increased cross section or of relatively greater thickness than the body 18 of the cover. On the under side of the cover is formed a depending flange 19. This flange is adapted to enter the groove 13 of the hollow receptacle and is formed, in all respects, to correspond therewith, having an inner vertical wall and an outer inclined wall, as shown. The flange extends entirely around the cover, and the inner vertical wall of the flange is aligned with the inner surface of the thickened marginal portion.

The bottom and side walls of the hollow receptacle are reinforced by a suitable reinforcing element 20, as shown, the upper ends of the reinforce in the side and end walls being branched, as at 20', to form a Y. The reinforce 21 of the cover extends substantially horizontally and is then bent downwardly through the thickened portion into the depending flange, as shown at 21' to serve not only to reinforce the cover and depending flange, but when the cover is mount-

ed on the hollow receptacle, a portion of the reinforce in the depending flange is arranged between the branch of the Y and in this manner a continuous reinforce is obtained.

In order to effect relief in the event of burial alive, the cover of the vault is provided with a main vent 22. This vent is, however, normally sealed by frangible and 10 preferably transparent means 23 which may be a disk of glass seated in the concrete, or material forming the cover, and so serving to normally seal the vent. This frangible means is preferably seated within the cover 15 while the said material is in a plastic state and is thereby properly embedded in this material. In order to prevent the frangible means 23 from being destroyed or otherwise broken from the exterior, the other end is 20 provided with a closure plug 24 threaded in a flange bushing 25 secured in the vent, as by being placed to set therein while the material is plastic, and having its flange flush with the top wall of the cover; the 25 closure has its top surface also flush with the flange and consequently with the cover when it is screwed into position. This closure plug may be provided with a plurality of smaller vents or it may be arranged to 30 be readily removed from the exterior.

In practice, the hollow receptacle having been seated in the ground, as shown, and the remains have been placed therein, the desired quantity of plastic bond, which may 35 be cement or similar substance, is deposited in the groove 13 in the top edge of the side and end walls of the hollow receptacle; the cover member is then placed upon the hollow receptacle with the depending flange thereof 40 entering the groove 13. The flange acts upon the plastic and serves to force the same upwardly in the spaces between the walls of the flange and the walls of the groove. It is to be noted in this connection, however, 45 that in the inner spaces, that is in the spaces

between the vertical walls of the groove and flanges, extend to a much higher level than the outer inclined spaces, and this prevents the plastic from being forced into the interior of the vault and thereby desecrating the same; any excess of plastic deposited in the groove is forced outwardly through the inclined spaces where it may be removed or finished with a trowel or the like if desired. 50

When the plastic bond is hardened a unitary structure of great strength and durability is presented, as the reinforce of the concrete is substantially continuous and the physical connection of the cover to the hollow receptacle is one of maximum efficiency. 55

I claim:

A burial vault comprising a hollow receptacle including a bottom wall and integral side and end walls having a groove formed in their top surfaces extending entirely 60 therearound, and a flange upstanding above said top and contiguous with said groove and extending entirely around the inner marginal portion thereof, said groove having an outer wall inclined upwardly and 65 outwardly and an inner vertical wall coincident with the contiguous wall of said flange, a cover having a depending flange adapted to fit in said groove and having a vertical wall and an inclined wall corresponding with the respective walls of said groove, a plastic bond adapted to be positioned in the spaces between the walls of 70 said groove and said depending flange to unite said cover to said hollow receptacle, 75 a reinforcement in the bottom, side, and end walls of said hollow receptacle and having its upper ends in the side and end walls branched to each side of said groove to form a Y, and a reinforcement in said cover having its ends extending in the said depending flange and positioned between the branches of the Y in assembly, all as and for the purposes set forth. 80

JOHN THOMAS ELMORE. 85
